UNITED STATES PATENT OFFICE.

JOSEPH LEDERER, OF NEW YORK, N. Y.

DESIGN FOR A CHANDELIER.

49,218.

Specification for Design.

Patented June 20, 1916.

Application filed December 23, 1915. Serial No. 68,457. Term of patent 7 years.

To all whom it may concern:

Be it known that I, JOSEPH LEDERER, a citizen of the United States, and a resident of the borough of Manhattan, city, county, and State of New York, have invented a new, original, and ornamental Design for a Chandelier, of which the following is a specification, reference being had to the accompanying drawing, forming part thereof.

The figure is a perspective view of a chandelier, showing my new design.

I claim:

The ornamental design for a chandelier as shown.

JOSEPH LEDERER.

Witnesses:

PATRICK A. BOLGER,
ISAAC B. OWENS.
